UNITED STATES PATENT OFFICE.

RICHARD KRAUSE, OF NEW YORK, N. Y.

DESIGN FOR AN EMBOSSED FABRIC.

SPECIFICATION forming part of Design No. 18,604, dated September 11, 1888.

Application filed August 10, 1888. Serial No. 282,467. Term of patent 3½ years.

To all whom it may concern:

Be it known that I, RICHARD KRAUSE, of the city, county, and State of New York, have invented a certain new and original Design for Embossed Fabrics, of which the following is a specification.

In the accompanying drawing a face view of my new design for embossed fabrics is shown.

The leading feature of my design consists in raised meniscus-shaped and comma-shaped ornaments in close proximity to each other.

A A represent meniscus shaped raised ornaments. B B represent comma shaped raised ornaments. Said meniscus shaped and comma-shaped ornaments are arranged indiscriminately and irregularly on the surface of the fabric and in close proximity to each other,

whereby irregular and fanciful recessed lines are formed between and around said meniscus and comma shaped ornaments. 20

Having thus described my invention, I claim as new and desire to secure by Letters Patent—

The design for embossed fabrics, as herein shown and described, the same consisting of 25 raised meniscus - shaped and comma - shaped ornaments arranged irregularly in close proximity to each other, substantially as set forth.

In testimony that I claim the foregoing as my invention I have signed my name in presence of two subscribing witnesses.

RICHARD KRAUSE.
